UNITED STATES PATENT OFFICE.

AXEL G. J. RAPP, OF CHICAGO, ILLINOIS, ASSIGNOR TO LINK-BELT COMPANY, OF CHICAGO, ILLINOIS, A CORPORATION OF ILLINOIS.

COKE-WHARF.

1,201,499.

Specification of Letters Patent. Patented Oct. 17, 1916.

Application filed November 21, 1914. Serial No. 873,298.

To all whom it may concern:

Be it known that I, AXEL G. J. RAPP, a citizen of the United States, residing at Chicago, in the county of Cook and State of Illinois, have invented a certain new and useful Improvement in Coke-Wharves, of which the following is a specification.

My invention relates generally to improvements in coke wharves such as are used for cooling and distributing the coke after it has been quenched.

It has for one object to provide a new and improved means of distributing and controlling the movement of the coke from the wharf where it is cooled, to the discharge conveyer.

Other objects of my invention will appear in the following.

My invention is illustrated more or less diagrammatically in the accompanying drawings wherein,

Figure 1 is a section on a transverse plane. Fig. 2 is a section along the line 2-2 of Fig. 1. Fig. 3 a detail on a plane similar to plane of Fig. 1, but showing a modified form.

Like parts are indicated by like letters in the drawings.

A is the inclined foundation floor of the coke wharf made up of masonry, concrete or other suitable material.

A¹ is a shield or cover of iron or other suitable material resting upon the floor A, and projecting at its lower end downwardly beyond the lower terminal of the floor A into a conveyer and feeder gallery A². In this gallery is located a feeder roll A³ having its center of rotation as indicated slightly below and to one side of the end of the shield A¹ so that the lower edge of the shield A¹ is substantially bounded by the surface of the smooth feeder roll A³.

A⁴ is a motor rotating the feeder roll in a counter clockwise direction. It will be noted that the feeder roll is made up in my preferred form in two sections which are driven independently though it will be obvious that any number of sections might be used and that they might be driven independently or in unison as the case may be.

A⁵ is the usual type of belt conveyer located in the gallery A² beneath the discharge side of the feed roll A³.

B is a vertical stop wall made up of plates or bars as the case may be. It terminates at

a point above the surface of the shield A¹, so as to leave a comparatively wide passage between the lower edge of the wall B and the surface of the shield A¹.

B¹ are supporting beams interposed between the wall B and the top of the wall B² to hold the wall B in position, and to provide a firm support for a portion of the operating mechanism.

B³ is a horizontal beam supporting the lower edge of the wall B. From it project upwardly and downwardly the brackets B⁴, B⁵, upon which are pivotally mounted the links B⁶, B⁷, which pivotally carry the gate B⁸. It will be noted that the gate B⁸ is in reality a grid made up of a series of parallel more or less upright bars, and this gate rests when in its normal position upon the shield A¹, and blocks the passage between the shield A¹ and the wall B. It will be noted that the links B⁶, B⁷ are of different lengths, that they are inclined one to the other, so that when the gate is lifted, being guided by the two links, it will assume a position inclined to its normal position of rest. The result of this is, of course, to assist in breaking the gate away from the pressure of the material resting on the shield A¹.

C is a lifting link pivoted at one end to the upper portion of the gate B⁸, the other end to one end of a bell crank lever C¹. This bell crank lever is rotatably mounted on the beam B¹, has its other end balanced by a counterweight C², and is limited in its clockwise movement by the stop C³ in which position the counterweight C² tends to thrust the bell crank in a clockwise direction, and thus locks the gate.

C⁴ is a control lever projecting rearwardly from the bell crank lever to a point where it can be manipulated by an operator standing on the operating or working platform C⁵. When the lever C⁴ is in the position shown in dotted lines, it is pressed against the stop by the counterweight when the gate is held open, permitting discharge of the material.

In the modified form shown in Fig. 4, the bell crank and link mechanism with its counterweight and locking arrangement is dispensed with, a short link D is used, and this link is pivoted at one end on the gate, at the other end on a simple lever D¹, which simple lever D¹ is pivoted on a bracket D². D³, D⁴ are latches on the stan-

chion D⁵ to lock the lever D¹ in the open and shut position as the case may be.

It will be evident that while I have shown in my drawings an operative device, 5 still many changes might be made in form, size, shape and arrangement of parts, without departing materially from the spirit of my invention. I wish, therefore, that my drawings be considered as in a sense dia- 10 grammatic.

The use and operation of my invention are as follows:—The coke which has of course previously been quenched, is dumped on to the coke wharf by any suitable means 15 not forming a part of my invention, and not here shown. As it is so dumped, it tends to travel down the shield, and will discharge into the conveyer gallery were it not stopped by the swinging gate. It 20 piles up against the gate, and also against the vertical wall above the gate until the bin formed by the wharf, the gate and the wall is completely filled. When the operator desires to discharge the coke from the wharf, 25 he does so by pulling down on the control lever until the lever is locked in the open position, thus lifting up the gate, and since the gate is so hung that it swings away from the coke, it will be understood that this is 30 comparatively easy. The coke then slides down the inclined surface of the wharf and is gradually fed over the roll feeder at the end of the wharf floor, and distributed thereby upon the conveyer. It will be noted that 35 the gate in its closed position is inclined to the surface of the wharf, and has a curved surface up which there is of course a tendency for the coke to ride, and thus there is no tendency for the coke to force the gate 40 open. This, of course, would tend to hold the gate shut were it not for the fact that the rapid movement of the gate combined with the peculiar hanging of the gate, which causes it to recede from the coke surface 45 more quickly than the coke can catch up, enables it to be broken out and lifted easily. It will be noted that the curved lower portion of the gate is curved about a radius but little shorter than the radius of the cir- 50 cle traveled by the gate as it is lifted. The result is that the gate may be moved back and forth with a very slight resistance on the part of the coke or material on the wharf

without interfering with the breaking away feature which enables the gate to be easily 55 manipulated.

I claim:

1. The combination with an inclined, supporting and feeding floor of a wall substantially vertically disposed, terminating above and out of contact with the floor, a gate adapted to close the space between the lower edge of the wall and the floor, the upper portion of the gate being substantially rectilinear, the lower portion of the 65 gate being curved forwardly toward the flow of material on the floor, a plurality of supporting, pivoted links, pivoted at one end on the wall, at the other end on the gate, these links being arranged in two groups, 70 one group being pivoted to the extreme upper edge of the gate, the lower group pivoted to the gate approximately at the upper boundary of the curved portion, and means for raising and lowering the gate independent 75 of such links.

2. The combination with an inclined, supporting and feeding floor of a wall substantially vertically disposed, terminating above and out of contact with the floor, a gate adapted to close the space between the lower edge of the wall and the floor, the upper portion of the gate being substantially rectilinear, the lower portion of the gate being curved forwardly toward the flow of material on the 80 floor, a plurality of supporting, pivoted links, pivoted at one end on the wall, at the other end on the gate, these links being arranged in two groups, one group being pivoted to the extreme upper edge of the gate, 85 the lower group pivoted to the gate approximately at the upper boundary of the curved portion, and means for raising and lowering the gate independent of such links, the pivot point of such group of links on the 90 wall being separately arranged one above the other and one nearer the wall than the other, the lower pivot point or line being closer to the wall than the upper one.

In testimony whereof, I affix my signature 100 in the presence of two witnesses this 13th day of November, 1914.

AXEL G. J. RAPP.
